MULTI-STATION SHOWER FIXTURE WITH SLOPING SHOWER HEAD PANEL

Hugh H. Logan, Glendale, George I. Doty, La Canada, and James F. Nelson, Woodland Hills, Calif., assignors to The Logan Manufacturing Company, Glendale, Calif., a corporation of California

Continuation of application Ser. No. 186,705, Apr. 11, 1962, which is a continuation of application Ser. No. 19,270, Apr. 1, 1960. This application Oct. 9, 1963, Ser. No. 315,740

6 Claims. (Cl. 4—145)

This application is a continuation of our copending application, Serial No. 186,705, filed April 11, 1962, entitled Multi-Station Shower Fixture With Sloping Shower Head Panel, now abandoned, which was a continuation of our parent application, Serial No. 19,270, filed April 1, 1960, also entitled Multi-Station Shower Fixture With Sloping Shower Head Panel, now abandoned.

This invention deals generally with multi-station shower fixtures of the type used in schools, industrial establishments, and the like and has as its primary object to provide a multi-station shower fixture having a number of unique features, including conservation of hot water, increase in simplicity of construction and corresponding decrease in cost of manufacture, improved structural stability, and increased ease of both installation and maintenance.

In one of its principal and preferred forms, the multiple shower fixture of the invention comprises a free-standing, floor-mounted vertical column in the form of an inverted cone or conical shell, about which are mounted a plurality of shower heads affording a plurality of shower stations. A prior art shower fixture intended for the same general purpose has used a stanchion in the form of a vertical pipe column extending between and fixed at both the floor and the ceiling. On an intermediate portion of this pipe column was mounted, by an arrangement of clamps, an enlarged shell of polygonal cross section, affording a plurality of vertically disposed panels, each of which mounted a shower head and a valve handle. Hot and cold water supply piping was contained inside the shell, supplied by means of exposed hot and cold water pipes running, for instance, into the top of the polygonal shell, outside the pipe column. This prior art fixture was characterized by two main components, a pipe column fastened to both floor and ceiling, and a housing shell clamped onto an intermediate portion of the pipe column. The lower end of the pipe column of such a fixture is then mounted on a drain device which is sunk into the shower room floor.

It should be understood that shower fixtures for institutional uses are subject to hazards, misuse and vandalism far beyond normal home or even factory expectations, and must, therefore, be fabricated with a view to defeat the various kinds of efforts which may be made to mutilate, take apart, deform, break down or tear away the equipment. A pipe column type installation of the prior art type mentioned in the preceding paragraph, with its anchorages at both the floor and ceiling, is fairly well capable of defeating ordinary efforts to bend it or break it loose by exertion of lateral force on the pipe column. However, if either anchorage were to be omitted, say that at the ceiling, the column could be rocked back and forth quite easily by force exerted at its upper end, and it would be easily subject to damage by such activity.

A purpose of the present invention is to simplify the structural make-up and organization of a multi-station shower fixture of the type mentioned, improve the lateral stability thereof, while holding the overall bulk of the fixture at a substantial minimum, and at the same time eliminate the necessity for anchoring the column both top

2

and bottom. Taking into account the vandalism commonly practiced in modern times in such places as institutional shower rooms, a further purpose of the invention is to defeat in as simple a manner as possible the anticipated efforts of those so inclined to bend or deform the installation, or break it free of its mounting. In meeting these stated purposes, the invention combines the structural components of the fixture into a single simple shell structure of unique form and minimized bulk which contributes such improved structural integrity that a simple mounting at one end thereof suffices for the necessary strength and stability of the fixture, enabling it, among other things, to resist successfully efforts to break it from its mounting by attempts to rock it from side to side.

15 A further specific object of the invention is the provision, in a column-type multi-station shower fixture, of a unique form of housing or shell which at once combines the features of extreme simplicity of construction and low cost of manufacture, attractiveness of appearance, natural 20 accommodation to the equipment necessary to be housed therewithin, inherent structural strength and lateral stability, as against both lateral thrusting and vibration, and ease of installation and maintenance.

A further purpose and corresponding improvement afforded by the invention is the location of the shower heads and valve handles on a slanting panel, the shower heads substantially outward of the valve handles, such as to constrain the bather to stand closer than usual to the shower heads. A compact, so-called institutional-type shower 30 head, rather than one on a long extended arm (such as is subject to vandalism), is used on the slanting panel. Notwithstanding the compact shower heads, the nozzle tips thereof are thereby naturally positioned in relative closeness to the bather when the bather stands with his hand 35 conveniently positioned for the water valves which are positioned lower on the same slanting panel. Since the heat loss from the shower water increases substantially with the distance between the shower nozzle and bather, this arrangement, i.e., the bather being encouraged or 40 constrained to stand substantially closer to the shower nozzle, results in considerable conservation of heat. The amount of heat so conserved during a single shower bath is, of course, small, but multiplied by a large number of bathers per day, and multiplied further by the number of 45 days the shower facility may be in use during a year, reveals a material money saving.

The invention in its preferred form broadly attains the aforementioned objectives by the simple but ingenious substitution, for the pipe column stanchion and clamped 50 on housing of the prior art, of a combined housing shell and column in the simple form of an inverted cone. Such a cone naturally affords the desired slanting surface or panel for mounting of the shower heads and valves, whereby the nozzle tips are positioned outboard of the valve 55 handles, as referred to earlier. To the small bottom end of the cone is fixed a flat mounting plate, and the entire fixture is mounted in place in the shower room by simply lifting it into position, with this flat plate engaging a seat on the floor drain, and then installing screws downward 60 through said plate into the floor drain. Hot and cold water pipes extend upward through the center of the floor drain, and couple readily with corresponding pipes inside the shell. The installation is so simple that it can be accomplished by two men in less than ten minutes. Moreover, it is strong, stable, and resistive of all ordinary efforts to harm it, such as by attempting to rock it.

The cone or conical shell very simply and ingeniously fulfills the desired functions mentioned hereinabove. The enlarging cross section in the upper direction, continuous from base to top, results in progressively greater stiffness in the upward direction, and corresponding re-

sistance to lateral deflection and vibration. Secondly, the large conical upper end portion of the inverted cone accommodates nicely the valves, manifolds and other piping necessary to be received in that part of the shell, while below this enlarged upper end portion, the cone tapers down continuously and without weakening steps or offsets to a diameter at the mounting base which remains adequate for necessary stiffness at that point.

The invention in some of its aspects may also be embodied in certain modified forms, some of which will be described hereinafter.

The invention may be best understood from the following detailed description thereof, taken in connection with the annexed drawings, wherein:

FIG. 1 is a view in side elevation and partially in section of the present free-standing shower fixture;

FIG. 2 is a top plan view of the fixture of FIG. 1;

FIG. 3 is an enlarged section through one of the soap dispensers on the fixture of FIG. 1;

FIG. 4 is an enlarged longitudinal section through a portion of the fixture of FIG. 1;

FIG. 5 is an enlarged section taken along line 5—5 of FIG. 1; and

FIG. 6 is a section taken along line 6—6 of FIG. 4.

The shower fixture 10 illustrated in FIGS. 1—6 of these drawings comprises an upper sheet metal housing or shell 12 and a lower base 14 for mounting the shell 12 in an upright position on the floor 16 of a shower room. Base 14 has been illustrated as comprising a drain which is embedded in the floor 16. It will become clear as the description proceeds, however, that other types of mounting bases may be used on the fixture.

Shell 12 comprises a one-piece sheet metal structure having the unique inverted conical shape illustrated. When installed, the large diameter end of the shell is uppermost. As will presently be seen, this inverted conical shape of the shell contributes several unique and highly important functions and advantages.

Rigidly fixed to the lower, small diameter end of the shell 12, and disposed in a plane perpendicular to the longitudinal axis of the shell, is a flat, outwardly turned mounting flange or plate 18. This mounting flange or plate seats on a flat upper seating surface 20 on the base 14. Screws 22 are inserted through holes in the mounting plate 18 and threaded into the base 14 for rigidly securing the shell 12 to the base.

As mentioned earlier, the base 14 is illustrated as comprising a drain. This drain includes a circular drain body 24 having an upstanding, center boss 26, the upper end of which is machined to provide the aforementioned seating surface 20. Drain body 24 defines an annular drainage space 28, the bottom wall of which slopes to the right, as the drain is viewed in FIG. 1. Extending generally tangentially from the drain body 24 is an outlet 30 adapted for connection to a drain line 31 in the floor 16.

Attached to the upper circular edge of the drain body 24 is a flanged ring 32. This ring has an upper flange 34 slightly below the plane of the floor surface. The drain cover 36, formed with a multitude of drain openings 38, is bolted to the ring flange 34. The drain cover 36 has a center opening 40 through which the lower, small diameter end of the shell 12 extends.

The illustrated shower fixture provides a plurality of shower stations 42 uniformly angularly spaced about the fixture. Each shower station includes a shower head 44, preferably of a compact, institutional type, i.e., without a long arm, and a pair of hot and cold water valves 46 and 48, respectively. Shower heads 44 are mounted on the outside of the shell 12, adjacent its upper end, and are uniformly spaced about the upper end of the shell. The shower heads are attached to the shell by means of screws 50 which are inserted, from the inside

of the shell, through holes in the shell wall and are threaded into the body of each shower head.

The hot water valves 46 are mounted directly over their associated cold water valves 48. Each of these valves comprises a valve body 52 mounted in any convenient way within the shell and a valve handle 54 located on the outside of the shell.

Piping for conveying water to the shower heads comprises a pair of hot and cold water supply pipes 60 and 61, respectively, in the base or drain 14. These pipes 60 and 61, which are connected to water supply pipes (not shown) in the floor 16, are exposed through the upper face 20 of the boss 26 to the lower, small diameter end of the shell 12.

Extending axially through the lower end portion of the shell 12 are a pair of hot and cold water pipes 63 and 64. The lower ends of these latter pipes are releasably coupled to the upper ends of the supply pipes 60 and 61 in the base 14 by quick connect and disconnect couplings to facilitate installation and to permit the shell 12 to be readily removed from the base, when desired. This can be accomplished by providing simple slip couplings 60' and 61' between the pipes, as shown in the drawings. O-ring seals may be used to seal the couplings, as indicated. Accordingly, to install the fixture, it is simply lifted to a position above the floor drain, the pipes 63 and 64 guided into the slip couplings, and the mounting flange or plate 18 then lowered onto the drain seat 20. Insertion of screws 22 and placement of drain cover 36 then completes the installation. The shell may be removed for repair, of course, by reversing these simple steps.

Pipes 63 and 64 extend upwardly through the shell 12 and terminate at the approximate level of the valves 46 and 48, respectively. The upper end of the hot water pipe 63 terminates somewhat above the upper end of the cold water pipe 64, as may be readily observed in FIG. 4. A cold water manifold ring 65 is connected to the upper end of the cold water pipe 64. Similarly, a hot water manifold ring 66 is connected to the upper end of the hot water pipe 63. The manifold rings 65 and 66 extend about the inside of the shell 12 and are located in planes perpendicular to the axis of the shell. For convenience, the hot and cold water valves 46 and 48 are located between these planes.

Each hot water valve 46 has an upper inlet 68 connected to the hot water manifold ring 66. Each cold water valve 48 has a lower inlet 70 connected to the cold water manifold ring 65. The outlets of each pair of hot and cold water valves are connected by a T 74. Extending from each T to the adjacent shower head 44 is a riser 76. From this description, it is evident that cold water flows to the fixture through the cold water pipe 61 in the base 14 and flows upwardly to the cold water manifold ring 65 through the cold water pipe 64 in the shell 12. Similarly, hot water flows to the fixture through the hot water pipe 60 in the base 14 and then flows upwardly to the hot water manifold ring 66 through the hot water pipe 63. When one of the cold water valves is opened, water flows from the cold water manifold ring 65, through the valve, and the associated riser 76 to the respective shower head 44. When one of the hot water valves is opened, hot water flows from the hot water manifold ring 66 to the associated shower head. If both valves of a shower station are opened, of course, both hot and cold water flow to the associated shower head, the hot and cold water becoming mixed during flow through the riser 76.

Also mounted on the shell 12 are a plurality of liquid soap dispensers 78. These soap dispensers are supplied with liquid soap from a soap tank 80 mounted within the upper end of the shell 12. This soap tank is mounted in any convenient way, such as by means of brackets 82 which are clamped to an adjacent pair of risers 76. The liquid soap is conveyed from the tank to the dispensers

78 through a manifold ring 84 and a riser 86 which extends from the ring 84 to the soap tank 80. Soap dispensers 78 have nipples 88 which are inserted through holes in the shell 12 and are threaded in radial outlets 90 on the soap manifold ring 84. The dispensers are attached to the shell 12 by nuts 92 threaded on the inner end of the dispenser bodies.

Extending from the upper end of the soap tank 80 is a vent pipe 94. The soap tank is filled through a filler fitting 96 which extends through an opening in the shell 12 at a point midway between a pair of adjacent shower stations.

The upper ends of the shell 12 is closed by a cover 98. This cover is removable to permit access to the inside of the shell 12 through its upper end. Such access is necessary for initial assembly and subsequent servicing of the shower fixture.

From the preceding description, it is evident that the shower fixture of FIGS. 1-6 has a substantial number of unique functional features and advantages. One of these is the inherent vandal-proof design of the present sloping panel and shower head arrangement, in combination in a component geometry which tends inherently to save on hot water. In this connection, the invention takes account of the fact that the nearer the bather stands to the shower head, the less hot water will be consumed, since the ejected spray rapidly loses heat in its travel from the shower head to the bather.

In the past, forward placement of shower heads, i.e., near the bather, has commonly been accomplished by the use of goosenecks or other forwardly extending supports for the shower heads. These existing shower head supports are undesirable, especially for school use, however, since they are frequently damaged by students hanging on them. According to the invention, compact, institutional-type shower heads are employed, avoiding long arms of goosenecks which are subject to damage as described. These shower heads are mounted directly on the inverted cone or conic side wall, which is of sufficiently large radius at the location of the shower heads, and sufficiently lesser radius at the lower elevation of the valve handles thereon, that the valve handles are thereby located rather substantially inward of the shower head nozzle tips, and the consequence is that the average bather, in order to be within convenient reach of the valve handles, automatically stands relatively closer to the shower head than he would otherwise do. It will be clear that with given shower heads and valves handles, projecting given distances outward from the side wall of the fixture, the outwardly sloping disposition of the side wall of the invention positions the shower heads substantially outward of the positions they would occupy relative to the valve handles were the side wall to be vertical between the shower heads and valve handles, as in the past. As heretofore described, this represents a conservation of hot water which, for a substantial number of shower fixtures, and over a period of time, has very material significance.

Another advantage of the fixture is that the one-piece conic shell 12 functions not only to afford a sloping mounting panel for the several shower heads, valves, etc., but the same simple structure serves and functions ideally as a strong, laterally stable, single-component supporting column, of minimized bulk for the functions it is called upon to fulfill. This is in contrast to the more complicated and costly existing free-standing shower fixture designs in which a housing, which furnishes the panels for mounting the shower heads, valves and soap dispensers, and the supporting column for the housing comprise separate components which are joined in some way. The shower fixture, therefore, minimizes both the number and cost of required manufacturing operations and the precision of those operations. To be stressed again is the increased lateral rigidity, strength and stability of the

fixture due to the constantly increasing diameter of the conic shell 12. This increasing diameter of the shell also lends increased rigidity or resistance against lateral oscillation or rocking of the fixture as compared to one having a lower supporting column of constant, relatively small diameter.

It is evident that the simple, unique cone shape of the fixture ideally accommodates interior equipment. That is to say, the space occupied by the piping in the lower end of the shell 12, i.e., pipes 60, 61, 63 and 64, is relatively small so that the diameter of the lower end portion of the conical shell 12 necessary to accommodate this piping can also be small. The space necessary to conveniently accommodate the manifold rings, valves, and interconnecting piping, on the other hand, is relatively large in horizontal area, so that the upper end portion of the shell 12, in the region from the valves to the shower heads, must be of a larger diameter. Obviously, and as clearly appears from a consideration of FIGS. 1, 4 and 6, the inverted cone shape of the fixture uniquely fulfills these two functional requirements in a most simple and inexpensive manner.

A further feature is the great facility with which the shower installation may be dismantled for repair. After removal of screws 22, the shell and interior equipment is simply lifted from the floor drain base. It can then be laid on its side, the shower heads removed by taking out screws 50, and the valves freed by removing their handles and stems, the latter in accordance with common practice. The entire interior hot and cold water piping assembly is then free of the conical shell, and can be easily removed through the large end of the cone, or as easily replaced. The striking simplicity of these operations, made possible by the conical shape of the fixture, should be readily apparent.

It is evident that the shower fixture herein described and illustrated is fully capable of attaining the several objects and advantages preliminarily set forth.

While certain preferred embodiments of the invention have been disclosed for illustrative purposes, it should be understood that numerous other modifications in design, arrangement of parts, and instrumentalities are possible within the spirit and scope of the following claims.

We claim:

1. A shower fixture comprising:
a frusto-conical shell,
a mounting flange rigidly fixed to the small end of said shell and projecting outwardly therefrom,
a plurality of shower heads mounted on said frusto-conical shell at a circumferential spacing from one another in the region of the larger diameter portion of said shell,
a control valve for each shower head mounted on said shell and including an operating handle projecting outwardly from said shell, and
water piping within said shell leading to said valves and from said valves to said shower heads.

2. The subject matter of claim 1, wherein said water piping includes:

60 hot and cold water supply pipes running longitudinally through the frusto-conical shell from the small end thereof to points distantly spaced from said small end and at which said shell is of materially increased diameter,
65 hot and cold water manifold rings in said shell connected to said supply pipes at said points, said piping including connections between said manifolds and valves and pipes leading from said valves to said shower heads.

3. A shower fixture comprising:
a hollow column in the form of an inverted frusto-conical shell,
mounting means rigidly affixed to the smaller diameter lower end of said inverted frusto-conical shell,
a plurality of shower heads mounted directly on the

relatively large diameter upper end portion of said frusto-conical shell at circumferential spacing there-around,

control valve means mounted on said shell at a level below each shower head including a valve handle 5 means projecting outwardly from said shell, and water piping within said shell leading to said valve means and from said valve means to corresponding shower heads.

4. The subject matter of claim 3, wherein the angle of 10 inclination of said frusto-conical shell and the vertical distance between the shower heads and valve handle means mounted on said shell are such as to locate said shower heads a material distance outward beyond the positions occupied by the valve handle means. 15

5. A shower fixture installation comprising:

a frusto-conical shell,
a mounting plate fixed to the small end of said shell and projecting radially outwardly therefrom, said mounting plate being apertured to afford a water 20 pipe passage into the small end of said shell,
a plurality of shower heads mounted on said frusto-conical shell at a circumferential spacing from one another in the region of the larger diameter portion of said shell,
a control valve for each shower head mounted on said shell and including an operating handle projecting outwardly from said shell,
water piping within said shell leading to said valves and from said valves to said shower heads, said piping including water pipes in said shell running generally longitudinally thereof from the small end of said shell toward said valves, 25
a stationarily installed mounting fixture including a seat engageable by said mounting plate, together with fastening means for securing said mounting fixture against said seat,
external water supply pipes having end portions connected to said stationarily installed mounting fixture

and continued through said seat in the area encompassed by the small end of said shell, and slip coupling joints between said end portions of said external water supply pipes and said longitudinally running water pipes in said shell, said pipes and slip joints leading into said small end of said conical shell through said apertured mounting plate fixed to said small end of said shell.

6. A shower fixture installation comprising:
a hollow column in the form of an inverted frusto-conical shell,
a base fixture to be stationarily mounted on the floor of a shower room including a portion affording a horizontal seat for said column,
a mounting flange fixed to the small lower end of said shell and projecting horizontally outwardly therefrom, said mounting flange being engageable with said seat,
fastening means securing said flange against said seat, a plurality of shower heads mounted on said frusto-conical shell at a circumferential spacing from one another in the region of the larger diameter portion of said shell,
a control valve for each shower head mounted on said shell and including an operating handle projecting outwardly from said shell, and
water piping within said shell leading to said valves and from said valves to said shower heads.
